UNITED STATES PATENT OFFICE.

WILLIAM D. LABADIE, OF SOUTH BEND, INDIANA, ASSIGNOR OF ONE-HALF
TO JOSEPH G. DUCK, OF MILWAUKEE, WISCONSIN.

CELLAR OR CISTERNS DRAINER.

SPECIFICATION forming part of Letters Patent No. 699,959, dated May 13, 1902.

Application filed January 7, 1901. Serial No. 42,434. (No model.)

To all whom it may concern:

Be it known that I, WILLIAM D. LABADIE, a citizen of the United States, residing at South Bend, in the county of St. Joseph and State of Indiana, have invented certain new and useful Improvements in Cellar or Cistern Drainers; and I do hereby declare the following to be a full, clear, and exact description of the invention, such as will enable others skilled in the art to which it appertains to make and use the same.

My invention relates to an improvement in cellar or cistern drainers; and its object is to produce a device of this character which is portable, so that the same may be easily removed from and replaced in cellars or cisterns and which will automatically start into operation whenever the water reaches a certain level and stop as soon as the height of the water is lowered to a certain point.

My invention consists in a steam-pipe provided with a valve which is automatically operated by the rise and fall of a float connected thereto, combined with a perforated chamber connected to the lower end of said pipe, a steam-injector placed therein, and the pipe for carrying away the water, all of which is supported on a suitable base or stand provided with flat horizontal legs which are adapted to rest on the bottom of the cellar or cistern whereby the drainer may be removed and replaced at will, as will be more fully described hereinafter.

The accompanying drawing represents a perspective of a device which embodies my invention.

F represents a suitable base or stand which serves as a support for the operating parts, and consists of two horizontal legs H H, connected to the base of the ejecting-chamber E by the diverging arms L L, extended from the ends of the legs, and which is to be placed in a hole or cavity in a cellar or cistern and into which hole or cavity the water is intended to be drained.

By providing the drainer with a stand having the long horizontal legs the same is firmly

supported in the cellar and may be easily removed or submerged in a well without dislodging or removing the operating parts.

The steam which is to operate the drainer enters through the pipe G, which is provided with a valve A at any suitable point and to which valve is connected a float B. Whenever the water reaches a certain point, it begins to raise the float, and thus open the valve, so that the steam flows freely through, and as soon as the water falls to a predetermined level the valve again closes and the operation of the drainer instantly stops. The lower end of the steam-pipe G is turned upwardly and enters the chamber E of any suitable shape or size, and which is provided with a series of perforations through its lower part to freely admit the water. Inside of this chamber and in the vertical pipe C are placed a suitable number of cones D, through which the water is ejected from the chamber E by the steam which escapes from the lower end of the pipe G when the valve A is opened.

The apparatus above described is placed in a suitable recess or cavity which is formed especially for the purpose and into which the water drains. If the water does not reach that level which will cause it to operate the float B, no operation takes place; but as soon as the water begins to operate the float B and opens the valve the drainer is automatically brought into use, and all action ceases as soon as the water is lowered to that point where the falling of the float B causes the valve A to close, and thus shut off the flow of steam.

As the steam-pipe is connected with the boiler or other source of supply, the drainer is entirely automatic in its operation and requires no attention or watching.

Having thus described my invention, I claim—

In a drainer, the combination of a vertical steam-inlet pipe having two right-angular bends to dispose its discharge end vertically upward and an automatic float-valve to control the supply of steam, a stand having horizontal laterally-offset legs and converging

arms which terminate in a supporting-base to which the discharge end of the inlet-pipe is secured, a vertical ejecting-chamber having a series of perforations near its bottom supported on said base, ejecting-tubes in the chamber and a vertical discharge-pipe connected to the top of the chamber in alignment with the discharge end of the inlet-pipe and the tubes, the whole adapted to be sup-

ported on the stand whereby the drainer is 10 portable.

In testimony whereof I affix my signature in presence of two witnesses.

WILLIAM D. LABADIE.
